UNITED STATES PATENT OFFICE.

JOHN W. SMITH, OF ERIE, PENNSYLVANIA.

TURBINE.

No. 923,451.

Specification of Letters Patent.

Patented June 1, 1909.

Application filed November 13, 1906. Serial No. 343,259.

To all whom it may concern:

Be it known that I, JOHN W. SMITH, a citizen of the United States, residing in Erie, county of Erie, State of Pennsylvania, have 5 invented certain new and useful Improvements in Turbines, of which the following is a specification.

This invention relates to turbines for using compressed air and has for its object to simplify the construction of turbines so as to 10 materially decrease the cost of manufacture of the same and also increase the efficiency thereof.

My invention has for its object to provide 15 a core having grooves on its surface and enveloping said core by a shell or casing whereby the grooves of the core form guide-channels with the inner walls of the shell.

For this purpose my invention consists of 20 a guide-channel core for a turbine, having grooves on its surface, and the invention consists further of the combination of a guide-channel core having grooves and a shell inclosing said core and forming guide-channels 25 therewith; and the invention consists lastly of a plurality of nozzle-channels adapted to guide the motor-fluid from the outlet-ends of the buckets of a turbine-wheel to the inlet-ends of the same, said nozzle-channels having 30 their cross-sectional area contracted at their ends in proximity to the inlet-ends of the turbine-wheel buckets.

My invention consists further of certain 35 novel features and combinations of parts which will be fully described hereinafter and finally pointed out in the claims.

In the accompanying drawings, Figure 1 shows an elevation of my improved guide-channel core. Fig. 2 represents a vertical 40 transverse section of a portion of a turbine showing the guide-channel core shown in Fig. 1 inserted in its shell, Fig. 3 represents a vertical longitudinal section of a portion of another turbine, showing a modified form of 45 core inserted in its shell, and Fig. 4 represents a vertical transverse section of the core and shell shown in Fig. 3, taken on line 4—4.

Similar letters represent corresponding parts.

50 Referring to the drawings, the turbine-wheel B having buckets D, rotates in the casing A.

To impinge the motor-fluid against the buckets of the turbine wheel, means are provided for guiding the motor-fluid in the direction of and against the buckets. Such

means, among others, are, as is well known, nozzles, guide-chambers, guide-channels and nozzle-channels. Hitherto such means were cast or formed integrally with the casings of the turbine. My improvement consists in providing a guide-channel core having grooves, which, when the core is inserted in its shell or casing, form guide-channels for conducting the motor-fluid in the pre-determined directions desired.

In the drawings the core E has milled or casted and polished grooves E¹, E², E³, E⁴ and E⁵ on its surface. When such a core is inserted into its shell or casing H, these 70 grooves form with the inner wall of the shell, guide-channels, the groove E¹ being in alignment with the inlet I, and the groove E⁵ being in alignment with the outlet O. The shell or casing is machined out for receiving 75 the guide-channel core, and the core itself is machined in such a manner that those parts of the core not cut away to form the grooves, fit snugly against the inner wall of the shell so as to prevent any leakage. In Fig. 4 the 80 core is made of a bulging character as shown in Fig. 4 at M so as to guide the motor-fluid at a larger radius. The advantage of these improvements is that both the shell and core may be easily and efficiently manufactured, 85 as both parts are accessible in machining and polishing, which is very desirable.

The cores are secured to the shells by means of screws F, as shown in Fig. 2, or may be clamped in place, as is shown in Fig. 4, in 90 which case the shell is made of two parts, H¹ and H², and secured together by screw bolts F¹. I do not wish to be limited to this particular form of embodiment, as screws F might be used to secure the core to the form 95 of shell shown in Fig. 4, and the shell shown in Fig. 2 might be as readily split or made of two parts similar to the form of shell shown in Fig. 4. The shell shown may be either part of the turbine-casing, as shown in Fig. 2, 100 or may be a separate shell, as shown in Fig. 4. My invention becomes the more important in the construction of guide-channels of comparative small dimensions where for example from 5 cu. ft. to 1000 cu. ft. of 105 free motor-fluid or air is used per minute.

In the particular form of embodiment of my invention, I show a novel form of guide-channel, which consists in shaping the grooves of the core so as to form a plurality 110 of nozzle-channels or convergent-nozzles N¹, N², N³, N⁴, which have their ends contracted

in cross-sectional area in proximity to the turbine-wheel buckets. The effect of contracting the nozzles or channels is to accelerate the motor-fluid or air just before it impinges the buckets. Each nozzle is designed with a cross-sectional area to give a desired ratio of expansion from nozzle to nozzle. The operation is as follows:—Suppose the velocity of the air or other fluid in the first 10 nozzle to be 1200 ft. per sec., and the buckets to be moving at 300 feet per sec., the velocity extracted would be 600 ft. per sec. with a residual velocity of 600 ft. per sec. The channel or nozzle that catches the fluid from 15 the outlet ends of the buckets would need to be designed with twofold more cross-sectional area than the preceding nozzle that delivers the fluid. The fluid is guided around the nozzle core at this low velocity of 600 ft. per 20 sec. to reduce fluid friction. By contracting or nozzleing the channels at the discharge end expansion takes place and the fluid is accelerated, and again reaches a velocity of 1200 ft. per sec. just before impinging against the 25 buckets; this is repeated in each nozzle until the available energy is extracted. It is obvious that each nozzle when so designed represents a pressure stage and each nozzle will carry a pressure stage lower than the preceding 30 one. Nozzling the channels increases the efficiency materially. These nozzled-channels are preferably constructed or machined to a convenient radius that will form the most desirable curve for guiding the working 35 fluid with the least change of direction.

By the term "guide-channel" herein used I wish to be understood to include thereby channels whether of the same cross-sectional area throughout or not, nozzled-channels or 40 guide-chambers, or any other means for guiding the air. So the term "guide-channel core" is intended to include any core having any means on the surface thereof for guiding the motor-fluid or air, and be such means 45 either one or more. The core may be provided with one or more grooves so as to form when inserted into its shell, one or more "guide-channels".

The advantage of my improved construction is that the parts may be more easily and more efficiently manufactured than heretofore, and may be readily assembled or taken apart for repairs.

Having thus described my invention, I 50 claim as new and desire to secure by Letters Patent:

1. In a turbine, a core having communicating grooves on opposite sides thereof, a

single set of buckets co-acting with said grooves, and each successive groove being 60 of increased area whereby expansion of motive fluid is carried on in said core.

2. In a turbine, a core having a plurality of grooves on opposite sides thereof, the front end of one groove communicating with 65 the rear end of the next groove, each successive groove being of increased area, and the forwardly extending portions of the grooves having the least diameter intermediate the ends thereof. 70

3. In a turbine, a core having communicating grooves, a single set of buckets co-acting with said grooves, means for admitting motive fluid to one of said grooves, and means for exhausting the motive fluid from 75 another of said grooves.

4. In a turbine having a turbine wheel with buckets, a core member, and a plurality of channels thereon forming guide channels adapted to receive the motor-fluid from the 80 outlet ends of the buckets, and direct it against the inlet ends of the same, said channels having their cross-sectional area contracted at their ends in proximity to the inlet ends of the turbine wheel buckets. 85

5. In a turbine, a core having communicating grooves and a shell inclosing said core and provided with inlet ports communicating with one of said grooves and an outlet port communicating with another of said 90 grooves.

6. In a turbine having a turbine wheel with a single set of buckets, a core having communicating grooves, the cross sectional area of which is contracted at their ends in 95 proximity to the inlet ends of the turbine wheel buckets.

7. In a turbine, a detachable core having a series of grooves thereon, a single set of buckets co-acting with said grooves and a 100 shell closely engaging the sides of said core.

8. In a turbine, a detachable core having a series of grooves thereon, and a shell closely engaging the sides of said core, said shell having an inlet port communicating with 105 the first of said series of grooves, and an outlet port communicating with the last of said series of grooves.

In testimony, that I claim the foregoing as my invention, I have signed my name in 110 presence of two subscribing witnesses.

JOHN W. SMITH.
